UNITED STATES PATENT OFFICE

162,360

COMBINATION MAGNETIC RECORDER AND REPRODUCER

Clifford Brooks Stevens, Milwaukee, Wis., assignor to Webster Electric Company, Racine, Wis., a corporation of Delaware

Application August 19, 1950, Serial No. 11,854

Term of patent 14 years

(Cl. D26—14)

To all whom it may concern:

Be it known that I, Clifford Brooks Stevens, a citizen of the United States, residing at 8041 Gray Log Lane, Milwaukee, Milwaukee County, Wisconsin, have invented a new, original, and ornamental Design for a Combination Magnetic Recorder and Reproducer, of which the following is a specification, reference being had to the accompanying drawing, forming a part hereof.

Fig. 1 is a perspective view with the cover partly open of a combination magnetic recorder and reproducer showing my new design; and

Fig. 2 is a perspective view, on a reduced scale, with the cover closed.

I claim:

The ornamental design for a combination magnetic recorder and reproducer as shown.

CLIFFORD BROOKS STEVENS.
